(57) **CLAIM**

The ornamental design for chassis part of a toy vehicle, as shown and described.

DESCRIPTION

FIG. 1 is a perspective view of a chassis part of a toy vehicle in accordance with our new design.

FIG. 2 is a “front” elevation view thereof;

FIG. 3 is a “rear” elevation view thereof;

FIG. 4 is an elevation view of the “right” side thereof, the elevation view of the “left” side being a mirror image thereof;

FIG. 5 is a “top” plan view thereof; and,

FIG. 6 is a “bottom” plan view thereof.

The broken lines are for illustrative purposes only and form no part of the claimed design.
